UNITED STATES PATENT OFFICE.

WILLIAM W. WILCOX, OF CHICAGO, ILLINOIS.

BAGGAGE-CHECK.

SPECIFICATION forming part of Letters Patent No. 230,455, dated July 27, 1880.

Application filed March 5, 1880. (Model.)

To all whom it may concern:

Be it known that I, WILLIAM W. WILCOX, of Chicago, in the county of Cook and State of Illinois, have invented certain new and useful 5 Improvements in Baggage-Checks, of which the following is a specification.

This invention relates to baggage-checks adapted for checking back and forth over two or more different lines of railroads and to a 10 given station upon any one of the roads indicated upon its face.

Heretofore checks adapted for the above-referred-to purpose have consisted of a single brass plate having the roads indicated upon it and attached to a strap for securing it to the baggage, said strap having strung upon it a card of pasteboard with the name of the station written upon it, such card being usually termed the "destination" card. This class 15 of checks, owing to the exposed position and frailty of their destination-cards and the annoyance experienced in consequence of their frequent mutilation and detachment, are used to a very limited extent. Others consist of a 20 single brass plate with flanges embracing the destination-card, the detachment of which is prevented by passing the strap through a slot in one end of both plate and card, while in other devices the card is held and exposed 25 between two brass plates, one of which is bent at its ends and the other slotted to receive such ends said plates being held together by the strap passing through the bent ends or by a latch pivoted upon the slotted plate.

30 In all three of the devices last mentioned, should the plates be bent, which frequently happens, great difficulty is experienced, not only in detaching the card but in restoring the plates to their original shape for further use, and in some cases the plates are entirely ruined. Furthermore, these checks are not adapted for 35 checking both ways upon the same or different roads; but once having reached their destination, or the end of the road or roads, they must be returned without baggage to the place from whence they started.

The object of my invention is to produce a baggage-check substantially indestructible, which is easily put together and adapted for 40 checking baggage either way over two or more

roads, and from and to any station upon one or more of the roads indicated upon the plates.

In the accompanying drawings, in which similar letters of reference indicate the same parts, Figure 1 is a view of the obverse face 55 of a check embodying my invention with the straps attached; Fig. 2, a view of the reverse face of the same.

A represents a flat brass plate provided near its lower end with a rectangular opening, 60 through which is exposed a portion of a destination-card, B, corresponding in size to the plate. Between the opening and the upper end of the plate, and on the face thereof, are stamped, or produced by other suitable means, 65 letters indicating one or more different railroads, between which and the opening is the number of the check.

C is a similar plate, having the opening and the order of the lettering and number in reverse order—that is to say, the opening near the top and the lettering near the bottom, with the order of the words reversed and the number over the lettering.

Both of these plates and the destination- 75 card are provided near each of the ends with slots to receive a strap, D, slotted at each end in the usual manner, to which they are attached at one end by the ordinary slip-noose. The free end of the strap is then passed through 80 the slots in the other end of the plates and card, thus locking all three closely together and exposing the entire face of the plates and the card through its opening, the face of the other plate, and also its opening, being concealed behind the strap, which is then attached to the baggage with the exposed plate outward, the card being protected between the two plates and having the name of the destination-station written upon it.

The letters upon the plates for indicating 90 each of the two roads at opposite ends of the route differ in arrangement and size upon the separate plates—*i. e.*, on the plate A the road at the beginning of the route is indicated at 95 the top of the column in small letters, and the road at the terminus next below in large letters, (the intermediate road or roads, if any, are in small letters below the latter,) while on plate C the first-mentioned two roads are reversed 100

as to each other, both in position and size of letters, the intermediate roads maintaining their size of letters and position at the foot of the column, as on plate A.

- 5 With this arrangement and contrast in size of letters it will be seen that by shifting the free end of the strap from one face to the other of the plates the name of the road at the end of the route may be made conspicuous, so as 10 to be read at first glance, and the checks be used with equal facility toward or from either end of the route; and as the slots for the card are at opposite ends of the check when in use, it will also be seen that by turning it over, after 15 using the two first exposed faces, two clean ones will be presented, thus adapting the card to be used for four trips before having to replace it with a new one, and thereby effecting not only a saving in time but in cost, which 20 latter is of no small importance in view of the immense number of checks in daily use.

Owing to the simple construction of my plates they may be made without the use of complicated machinery or frequent handling, 25 and therefore cheaply produced, and if bent or

indented when in use they may be readily and quickly restored to their original shape by pressure or hammering with an ordinary hammer upon any smooth surface. They afford an effective protector to the destination-card, and 30 are readily put together or taken apart, no fastening being required except that of an ordinary strap, by which they are attached to baggage.

What I claim is—

In a baggage-check, the combination, with 35 two flat plates having upon their faces the number of the check and letters indicating the roads over which it is used, and provided near their opposite ends with openings, of an intermediate destination-card exposed through said 40 openings, said plates and cards being detachably and reversibly connected together by a strap passing through corresponding slots in the plates and cards, substantially as described 45 and shown.

WILLIAM W. WILCOX.
